US00D914024S

(12) **United States Design Patent** (10) Patent No.: **US D914,024 S**
(45) Date of Patent: **** Mar. 23, 2021**

(54) **DISPLAY SCREEN FOR TELEPHONE**

- (71) Applicant: **HUAWEI TECHNOLOGIES CO., LTD.**, Guangdong (CN)
- (72) Inventors: **Joon Suh Kim**, Guangdong (CN); **Ting Xu**, Guangdong (CN); **Zhenqi Tang**, Guangdong (CN); **Haibo Luo**, Guangdong (CN); **Ying Zhao**, Guangdong (CN); **Haiyan Hu**, Guangdong (CN); **Meng Li**, Guangdong (CN); **Ze Yuan**, Guangdong (CN)
- (73) Assignee: **HUAWEI TECHNOLOGIES CO., LTD.**, Shenzhen (CN)

(**) Term: **15 Years**

(21) Appl. No.: **35/506,454**

(22) Filed: **Sep. 21, 2018**

(80) **Hague Agreement Data**

Int. Filing Date: **Sep. 21, 2018**

Int. Reg. No.: **DM/103202**

Int. Reg. Date: **Sep. 21, 2018**

Int. Reg. Pub. Date: **Mar. 22, 2019**

(57) **CLAIM**

The ornamental design for a display screen for telephone, as shown and described.

DESCRIPTION

FIG. 1.1 illustrates a front view of a display screen for telephone showing our new design;

FIG. 1.2 illustrates a rear view thereof;

FIG. 1.3 illustrates a left view thereof;

FIG. 1.4 illustrates a right view thereof;

FIG. 1.5 illustrates a top view thereof;

FIG. 1.6 illustrates a bottom view thereof; and

FIG. 1.7 illustrates a front perspective view thereof.

1 Claim, 7 Drawing Sheets
